CLAIM

The ornamental design for a tray for a carrier, as shown and described.

DESCRIPTION

FIG. 1 is a top perspective view of a tray for a carrier showing my new design;

FIG. 2 is a side view thereof, the other side view being a mirror image thereof;

FIG. 3 is a front view thereof;

FIG. 4 is a rear view thereof;

FIG. 5 is a bottom view thereof;

FIG. 6 is a top view thereof;

FIG. 7 is a top perspective view of a carrier with tray showing the claimed design in an environment in which it may be used;

FIG. 8 is a left side view thereof;

FIG. 9 is a right side view thereof;

FIG. 10 is a front view thereof;

FIG. 11 is a rear view thereof;

FIG. 12 is a top view thereof; and,

FIG. 13 is a bottom view thereof.

The broken lines in the figures show portions of the carrier that form no part of the claimed design.

The shade lines in the figures show contour and not surface ornamentation.

1 Claim, 7 Drawing Sheets
